EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

AUTOMATICALLY-THREADING SHUTTLE.

1,017,065.

Specification of Letters Patent.

Patented Feb. 13, 1912.

Application filed November 9, 1911. Serial No. 659,290.

To all whom it may concern:

Be it known that I, EDWARD S. STIMPSON, a citizen of the United States, and resident of Hopedale, county of Worcester, State of Massachusetts, have invented an Improvement in Automatically-Threading Shuttles, of which the following description, in connection with the accompanying drawing, is a specification, like characters 10 on the drawing representing like parts.

This invention relates particularly to loom-shuttles of the type wherein the threading operation is effected automatically, and it has for its object the production of a loom-shuttle of the type referred to provided with a novel and improved eye-member, so constructed and arranged that it is held securely and positively in position in the shuttle body. By the improved 20 construction hereinafter described I am also able to employ an eye-member of porcelain, glass, or other suitable vitreous material when the use thereof is desirable.

In United States Patent No. 933,497 granted to me September 7, 1909, the eye-member is a longitudinally slotted tube of metal, such as hardened steel, fitted into a circular hole in the shuttle-body. This form of eye-member is held from rotative 30 and longitudinal movement by engagement with a part of the sheet-metal threading device, and is entirely satisfactory in many cases, but in certain kinds of weaving the filling is of such a character that it tends to 35 cut or score the metal of the eye-member, causing frequent filling breaks.

In the old forms of hand-threaded shuttles a tubular vitreous eye is of common occurrence, and it resists the cutting or scoring action of practically any kind of filling, but this material cannot be used in making 40 an eye-member of the character referred to because of its fragile nature, the shock and jar to which the shuttle is subjected in 45 weaving fracturing the eye-member.

In my present invention I have devised a novel form of eye-member for use in automatically threading shuttles, so constructed that it is held positively and securely in its 50 seat in the shuttle-body without any possibility of turning or moving in the direction of its length.

The eye-member to be hereinafter described can be made of metal, or of vitreous material when desired, and when made of the latter material it is not liable to fracture, the peculiar structure enabling the eye-member to resist the shock or hammering to which the shuttle is subjected.

The various novel features of my invention will be fully described in the subjoined specification and particularly pointed out in the following claims.

Figure 1 is a top plan view of the thread-delivering or eye end of a loom-shuttle embodying my present invention; Fig. 2 is a side elevation thereof, the shuttle-body being partly broken out to show a portion of the positioning and retaining flange of the eye-member; Fig. 3 is a similar view but with the eye-member and the threading member omitted; Figs. 4 and 5 are perspective views of the eye-member, detached, viewed from its outer and inner ends, respectively.

In the drawing the shuttle-body A has formed therein at its delivery end a longitudinal recess or thread passage 1 in which is seated a portion of the threading member, said passage communicating with a transverse U-shaped recess 2 extended through the side wall of the shuttle. As shown in Figs. 1, 2 and 3 this recess has its upright sides and curved bottom provided with a continuous groove 3, which is symmetrical in contour with the recess. This grooved recess can be very easily and quickly formed in the side wall of the shuttle by a suitable milling tool, and a circular saw, or a combination of the two, the bottom of the recess 85 and the groove being circular, as shown.

The eye-member B, shown separately in Figs. 4 and 5, fits in the recess 2, and will be again referred to, the threading member C, Figs. 1 and 2, being fitted into the thread 90 passage 1 and retained therein by a suitable bolt D. This threading member C is substantially that shown in my patent above referred to, and is made of sheet metal bent and shaped to assume control of the filling 95 thread and to direct and guide it automatically into the eye-member.

Inasmuch as the construction and functions of the threading member are well

known no further description thereof is necessary, except to state that the thread traverses the trough-like portion *c* on its way to the eye-member, and that the latter is held down in its seat by the usual projection or head *c'* of the threading member, as will be explained.

Referring now to Figs. 4 and 5, the eye-member B comprises a thick, strong body 4, externally U-shaped and of such dimensions that it will snugly fit into the recess 2, Fig. 2, said body having an external, integral and symmetrical flange 5 thereon between its inner and outer ends. This flange slides into and seats in the groove 3 of the recess 2, and it will be manifest that thereby the eye-member is held positively and securely from endwise movement in the side wall of the shuttle, the corresponding shapes of the flange and the groove 3 preventing any tendency of the eye-member to rotate. The delivery passage 6 in the body of the eye-member is provided with a V-shaped inlet at the top of the body 4, the sides of the inlet being formed by the flared surfaces 7, 8 constituting the upper end of the body, the upper ends of the flange 5 terminating at said flared surfaces. When the eye-member B is seated in the recess 2, see Figs. 1 and 2, the projection or head *c'* of the threading member C overhangs and seats upon the flared side 7 of the V-shaped inlet, retaining the eye-member seated in the recess, and the said flared side extends inward and abuts against the trough-like portion *c* of the threading member C. The clearance between the other flared side 8 of the inlet and the forward edge of the head *c'* permits the thread to travel through the V-shaped inlet into the delivery passage 6 of the eye-member during the threading operation, as will be manifest to those skilled in the art.

As shown in Fig. 5 the inner end of the body 4 is cut away at 9 to leave ample room for the thread as it is directed from the longitudinal thread passage to the transverse delivery passage 6.

By virtue of the shape and construction of the eye-member and the transverse recess and groove in which it fits the eye-member is held firmly but without any undesirable pressure in its proper position, so that it cannot move endwise or axially, and it is kept properly seated by the overhanging part *c'* of the threading member.

By reason of the thick and stocky body 4 of the eye-member, and the strong external flange thereon, said member can when desired be made of porcelain or other suitable vitreous material, which is so disposed that there is very little tendency to fracture.

Whatever the material of the eye-member it cannot become displaced by slight shrinkage of the shuttle-wood, for in all cases the upright opposite sides of the recess act upon

the adjacent straight sides of the body 4, and the flange 5 is under all circumstances seated in the groove 3. With a tubular eye-member there is a tendency to turn and work loose unless the fit of such member in the shuttle-body is made very accurately, and even then a slight shrinkage of the wood will tend to loosen up the eye-member in a very objectionable way.

Having fully described my invention, what I claim as new and desire to secure by Letters Patent is:

1. A shuttle having a thread passage in the end portion thereof, and a transverse U-shaped recess leading therefrom through the side-wall of the shuttle, said recess having its sides and bottom provided with a continuous groove, and an eye-member comprising a U-shaped body having an open thread inlet at its top, and adapted to fit in said recess, and having between its inner and outer ends an external integral and symmetrical positioning flange to seat in the continuous groove of said recess and prevent rotative or endwise movement of the eye-member.

2. A shuttle having a thread passage in the end portion thereof, and a transverse U-shaped recess leading therefrom through the side-wall of the shuttle, said recess having its sides and bottom provided with a continuous groove, and an eye-member comprising a U-shaped body having a V-shaped inlet at its top and adapted to fit in said recess and having an external, integral and symmetrical positioning flange to seat in the groove of said recess and prevent rotative and endwise movement of the eye-member, combined with a threading member detachably mounted in said thread passage and having a projection overhanging and seating upon one of the flared sides of the V-shaped inlet, to retain the latter seated in the recess.

3. A shuttle having a thread passage in the end portion thereof, and a transverse U-shaped recess leading therefrom through the side-wall of the shuttle, said recess having its sides and bottom provided with a continuous groove, and an eye-member comprising a U-shaped body having a V-shaped inlet at its top and adapted to fit in said recess and having an external, integral and symmetrical positioning flange to seat in the groove of said recess and prevent rotative and endwise movement of the eye-member, combined with a threading member detachably mounted in said thread passage and having a projection overhanging and seated upon one of the flared sides of the V-shaped inlet, to retain the latter seated in the recess, said flared side extending inward and abutting at its inner end against a portion of the threading member.

4. An eye-member for a self-threading shuttle comprising a U-shaped body having

a delivery passage and a V-shaped inlet at its top leading into said passage and having between its inner and outer ends an external, integral and U-shaped positioning flange symmetrical with the body, and terminating at the flaring sides of said V-shaped inlet.

In testimony whereof, I have signed my name to this specification, in the presence of two subscribing witnesses.

EDWARD S. STIMPSON.
